United States Patent Office

Des. 183,593
Patented Sept. 30, 1958

183,593

COMBINED WALL PLATE AND BOX COVER OR SIMILAR ARTICLE

Leonard Atkin, Springfield, N. J., assignor to Stone Manufacturing Co., a corporation of New Jersey

Application May 24, 1957, Serial No. 46,326

Term of patent 14 years

(Cl. D26—5)

FIG. 1.

FIG. 2.

FIG. 3.

FIG. 4.

FIG. 5.

FIG. 6.

Figure 1 is a top plan view of a combined wall plate and box cover or similar article showing my new design; Figure 2 is a cross section of Figure 1 taken along line 2—2 thereof;

Figure 3 is a bottom view thereof;

Figure 4 is a perspective view thereof;

Figure 5 is a cross-section of Figure 4 taken along line 5—5 thereof; and

Figure 6 is an enlarged fragmentary view of the flange showing the cross-lined surface.

I claim:

The ornamental design for a combined wall plate and box cover or similar article, substantially as shown.
